UNITED STATES PATENT OFFICE

2,439,700

HAT

Gerald H. Simon, San Francisco, Calif.

Application October 15, 1945, Serial No. 622,257

1 Claim. (Cl. 2—175)

1

An object of my invention is to provide a hat in which the crown is formed of a plurality of sectors whose edges abut each other and the means for connecting the sectors together so that they will conform to the inner curvature of the crown and therefore cause no discomfort to the wearer because the interior surface of the crown will be smooth.

A further object of my invention is to provide a hat crown in which grosgrain ribbon is used on the inner surface of the crown for securing the sections together. Such material will hold the section edges in abutting relation and still permit the crown to conform to the curvature of the head. My invention is simple in construction and provides novel means for interconnecting crown sectors together.

Other objects and advantages will appear in the following specification, and the novel features of the device will be particularly pointed out in the appended claim.

My invention is illustrated in the accompanying drawings forming a part of this application, in which:

Figure 1 is a perspective view of a hat showing the crown made of sections and secured together by my novel means;

Figure 2 is a side elevation of the crown on a larger scale, a portion of one section being broken away to illustrate the grosgrain ribbon; and

Figure 3 is a horizontal section through a portion of the crown, and is taken along the line III—III of Figure 2.

While I have shown only the preferred form of my invention, it should be understood that various changes or modifications may be made within the scope of the appended claim without departing from the spirit and scope of the invention.

In carrying out my invention, I provide a hat which has a crown indicated generally at A and a brim indicated generally as B. The brim may be secured to the crown in any well known manner. The crown is illustrated in detail in Figures 2 and 3. The crown is formed from a plurality of flexible and triangular shaped fabric sections 1. I have shown the crown as formed of eight sections, although I do not wish to be confined to any particular number. The abutting edges 2 of the adjacent sections are held in place by strips of grosgrain ribbon 3. Rows of stitching 4 paralleling the abutting edges 2 secure the adjacent sections to the same ribbon strip 3.

The ribbon will lie against the inner surface 5 of the sections. The usual way of securing hat sections together is to fold the sections adjacent to the edges 2 and stitch the folded portions together. This will form inwardly extending rib-

like portions which will bear against the head and cause discomfort. Moreover, additional material for the sections would be needed. By using grosgrain ribbon and parallel rows of stitching 4 placed close to the edges 2, the rib-like portions do not appear.

The ribbon is strong enough to prevent the edges from pulling laterally apart and yet the grosgrain effect will permit the sections to curve longitudinally from the top of the crown to the brim so as to conform to the curvature of the head. The particular manner of securing the sections together by ribbon permits the crown of the hat to be partially folded in order to be packed in a small space without causing any permanent fold to remain in the crown when the hat is again worn. The ribbon strips will permit the sections to fold with respect to each other along the lines of joining.

The outer appearance of the crown is enhanced because the lines 2 of joining between the crown sectors 1 will each be paralleled by two lines of stitching 4. The stitching will give a border effect to each crown section.

25 I claim:

A crown for a hat made up of a plurality of substantially triangular-shaped sections whose adjacent edges abut each other, the inner and outer surfaces of each section being arranged flush with the inner and outer surfaces, respectively, of the adjacent sections to preserve continuity of the inner and outer surfaces of the crown, flexible strips underlying the crown and covering each line of abutment defined by the sections, and rows of stitching paralleling the lines of abutment and placed close to the lines for securing the sections together in abutting relation, said flexible strips being grosgrain ribbon, whereby the sections may be folded with respect to each other along the lines of abutment and the transverse ribs of the grosgrain ribbon permits slight bending or folding of the sections along lines paralleling the transverse ribs to give the crown greater flexibility.
